UNITED STATES PATENT OFFICE.

RAYMOND N. EHRHART, OF EDGEWOOD PARK, NEW JERSEY, ASSIGNOR TO WESTINGHOUSE ELECTRIC & MANUFACTURING CO., A CORPORATION OF PENNSYLVANIA.

CONDENSER.

1,372,409.

Specification of Letters Patent. Patented Mar. 22, 1921.

Application filed November 21, 1917. Serial No. 203,262.

To all whom it may concern:

Be it known that I, RAYMOND N. EHRHART, a citizen of the United States, and a resident of Edgewood Park, in the county of 5 Allegheny and State of Pennsylvania, have made a new and useful Invention in Condensers, of which the following is a specification.

This invention relates to condensers and 10 has for an object to produce a jet condenser which may be readily converted into a surface condenser.

A further object is to produce a condenser which may be changed from one type 15 to another in accordance with changing water conditions, or with fluctuations in price of the material of which the condenser is made.

A further object is to produce a jet condenser which may easily and cheaply be converted into a surface condenser with practically no changes in the condenser shell originally provided.

These and other objects are attained by 25 means of a condenser embodying the features of my invention herein described and illustrated in the drawings accompanying and forming a part hereof.

Under certain conditions and in certain 30 localities it is desirable to employ surface condensers in preference to jet condensers. Surface condensers ordinarily require a large number of brass tubes, or tubes of some similarly noncorrosive metal. At 35 times the price of metal suitable for tubing rises so high that the cost of constructing a surface condenser becomes practically prohibitive. It may therefore be desirable to install the condenser as a jet condenser and 40 to later change over to a surface condenser when the price of tubing drops. Furthermore, a change of water conditions may make it desirable to change from one type of condenser to another at some time in the 45 future. My invention contemplates a condenser which may be changed from one type to the other in accordance with the varying conditions encountered. For example, if the condenser is installed while the price of tubing 50 is high, it can be arranged as a jet condenser and can later be changed to a surface condenser, when the price of tubing drops, with but comparatively few changes in the shell structure of the condenser.

55 In the drawings: Figure 1 is a diagram-

matic sectional view of a surface condenser which may be changed in accordance with my invention into a jet condenser.

Fig. 2 is a diagrammatic sectional view of the condenser illustrated in Fig. 1 changed 60 into a jet condenser in accordance with my invention.

Fig. 3 is a sectional view along the line 3—3 of Fig. 2.

The condenser illustrated in Fig. 1 includes a horizontal cylindrical shell 5, having a steam inlet port 6 at its top, and provided at one end with water boxes 7 and 8, constituting a double water box, and at the other end with a water box 9. As shown, 70 the shell 5 is traversed longitudinally by tubes 10, the ends of which are mounted in tube plates 11 and 12 and through which the water is circulated. The tube plates 11 and 12 are illustrated as secured in place between the ends of the shell 5 and the water boxes 7, 8 and 9.

The water boxes 7 and 8 each occupy one-half of one end of the condenser and are separated from each other by a partition 13. 80 The water box 9 occupies the whole of the other end of the condenser. In operation cooling water is delivered to the water box 7 through a port 14, flows through the lower tubes 10 into the water box 9, back through 85 the upper tubes 10 into the water box 8, and out through a port 15. A port 16 is provided in the end wall of the water box 9 for a purpose hereinafter to be described.

If the cost of tubing is prohibitive at the 90 time the condenser is built, and it is desirable to install the condenser as a jet condenser, the tubes 10 are omitted and the tube plates 11 and 12 are preferably omitted. As shown in Fig. 2, end plates 17 and 18 are 95 substituted for the tube plates 11 and 12. In place of the cooling tubes 10, I have shown two relatively large conduits 19 and 20 which extend longitudinally through the interior of the shell 5 from the end plate 17. 100 These conduits are in open communication with the water box 7 to which cooling water may be supplied through the port 14. On each of the conduits 19 and 20, I have shown a double row of nozzles 21, which are adapted to spray the cooling water into the condenser shell 5 in a finely divided form. The steam entering the shell 5 through the port 6 is condensed by direct contact with this water spray.

On the sides of the conduits 19 and 20, I have shown aprons 22, which form beneath them air pockets, where the air which leaks or is carried into the condenser collects. 5 The aprons form a combining cone between the conduits 19 and 20, and between each conduit and the shell 5. Air offtake ports 23 are provided in the end plates 18 below the aprons 22, and through them the air is withdrawn as it collects underneath the aprons. 10

The end plate 18 is shown as having an opening 18^a at its bottom so that the cooling water and condensate which collects in the bottom of the shell 5 may flow into the water box 9 and be withdrawn through the port 16 by a suitable pump 24.

In order to convert the condenser into a surface condenser, it is only necessary to remove the end plates 17 and 18, the conduits 19 and 20, and the aprons 22, and to insert instead the tube plates 11 and 12 and the tubing 10. It will, of course, be understood that the port 16 will be closed with a suitable flange and the port 15 connected 25 with a suitable discharge pipe. When arranged as a surface condenser the condensate may be withdrawn from the condenser through a centrally located condensate port 25. It will also be apparent that this port 30 may be made large enough to be employed in place of the port 16 when the condenser is arranged as a jet condenser. In this case the port 16 may be omitted.

The condenser illustrated forms either an 35 efficient jet or surface condenser, and when acting as a jet condenser the arrangement is such that the condenser embodies the distinguishing features of well known forms of jet condensers and therefore is capable of 40 the same high efficiency. When the cost of brass or the water conditions vary so that a surface type of condenser is preferable in this installation, the jet apparatus may be easily removed and the proper tubing inserted. 45

While I have described and illustrated but one embodiment of my invention, it will be apparent to those skilled in the art that various changes, modifications, substitutions, additions and omissions may be made 50 in the apparatus described and illustrated without departing from the spirit and scope of the invention as set forth by the appended claims.

55 What I claim is:

1. A condenser comprising a shell, an end plate closing one end of said shell and having conduits extending therefrom into the shell, means for delivering cooling water to 60 the conduits, nozzles in the conduits for spraying the water into the shell, means for forming combining cones and air pockets therein, and means for withdrawing the condensate and cooling water from the shell.

65 2. In a convertible condenser, the com-

bination of a condenser shell, a double water box element, one compartment of which is provided with an inlet port and the other of which is provided with an outlet port, a plate adapted to close communication between the interior of the shell and the compartment having the outlet port, and a jet condenser nozzle in communication with the compartment having the inlet port and projecting into the shell. 70

3. In a convertible condenser, the combination of a condenser shell, a double water box element, one compartment of which is provided with an inlet port and the other of which is provided with an outlet port, a jet 80 condenser nozzle extending within the shell and in communication with the compartment having the inlet port, and means for closing communication between the shell and the compartment having the outlet port. 85

4. In a convertible condenser, the combination of a condenser shell, a double water box element, one compartment of which is provided with an inlet port and the other of which is provided with an outlet port, 90 and a jet condenser nozzle extending within the shell and in communication with the compartment having the inlet port.

5. A condenser comprising a shell, an end plate closing one end of said shell and 95 having conduits extending therefrom into the shell, means for delivering cooling water to the conduits, nozzles in the conduits for spraying the water into the shell, means 100 forming combining cones and air pockets therein, and means for withdrawing the air from the said pockets.

6. A condenser comprising a shell provided with a pair of jet nozzles spaced apart and spaced from the side of the shell, and 105 aprons disposed with relation to the nozzles so as to form a combining cone between the nozzles and between each nozzle and the adjacent side of the shell, through which cooling liquid from the nozzles may pass. 110

7. A condenser comprising a substantially horizontal shell having end plates, a substantially horizontal jet nozzle disposed within the shell between the end plates, means for supplying cooling liquid to the 115 said nozzle, an apron extending between the said end plates co-operating with the nozzle and forming an air pocket, and means whereby air may be withdrawn from the said pocket. 120

8. A condenser comprising a substantially horizontal shell, means for delivering water spray to the interior of the shell, baffles extending longitudinally of the shell and forming therein a combining passage converging toward the bottom of the shell and forming air pockets within the shell, means for withdrawing noncondensable fluid from said air pockets, and means for withdrawing water from the interior of the shell. 125

9. A convertible condenser comprising a shell adapted to receive either surface or jet condensing elements, a double water box element for one end of the shell having inlet and outlet compartments, a water box element for the other end of the shell having water outlet means adapted for the attachment of a pump, and a jet condenser unit comprising end plates and a nozzle adapted 5 to be assembled in relation to said shell, one end plate closing communication between the shell and the outlet compartment and 10

affording communication between the inlet compartment of said double water box element and the other plate having an opening 15 near the lower portion thereof to afford communication between the shell and the other water box element.

In testimony whereof, I have hereunto subscribed my name this 19th day of November, 1917.

RAYMOND N. EHRHART.

Witness:

C. W. McGHEE.

It is hereby certified that in Letters Patent No. 1,372,409, granted March 22, 1921, upon the application of Raymond N. Ehrhart, for an improvement in "Condensers," an error appears requiring correction as follows: In the grant and in the heading to the printed specification the residence of the patentee is erroneously given as "Edgewood Park, New Jersey," whereas said residence should have been given as *Edgewood Park, Pennsylvania*; and that the said Letters Patent should be read with this correction therein that the same may conform to the record of the case in the Patent Office.

Signed and sealed this 3d day of May, A. D., 1921.

[SEAL.]

T. E. ROBERTSON,
Commissioner of Patents.
